(Cl. D61—1)

To all whom it may concern:

Be it known that I, Charles H. Frank, Jr., a citizen of the United States of America, residing at Merrick, in the county of Nassau and State of New York, have invented a new, original, and ornamental Design for a Camera, of which the following is a specification, reference being made to the accompanying drawing, forming a part thereof.

Fig. 1 is a front elevational view of a camera showing my new design.

Fig. 2 is a top plan view.

Fig. 3 is a rear elevational view.

Fig. 4 is a side elevational view.

I claim:

The ornamental design for a camera, substantially as shown.

CHARLES H. FRANK, JR.
